UNITED STATES PATENT OFFICE.

ANTON M. OPSAL, OF MINNEAPOLIS, MINNESOTA.

ARTIFICIAL LEG.

1,102,289.

Specification of Letters Patent.

Patented July 7, 1914.

Application filed March 5, 1914. Serial No. 822,552.

To all whom it may concern:

Be it known that I, ANTON M. OPSAL, a citizen of the United States, residing at Minneapolis, in the county of Hennepin and State of Minnesota, have invented certain new and useful Improvements in Artificial Legs; and I do hereby declare the following to be a full, clear, and exact description of the invention, such as will enable others skilled in the art to which it appertains to make and use the same.

My invention has for its object to provide improved means for producing natural forward swinging movements of the lower leg sections of artificial legs constructed for application to upper leg amputations, and to such ends, generally stated, the invention consists of the novel devices and combinations of devices hereinafter described and defined in the claims.

In the accompanying drawings which illustrate the invention, like characters indicate like parts throughout the several views.

Referring to the drawings: Figure 1 is a side elevation showing an artificial leg having my invention applied thereto; Fig. 2 is a view corresponding to Fig. 1 with some parts broken away and some parts sectioned; Fig. 3 is a side elevation showing in detail a rocker which constitutes one of the elements of the leg attachment; and Fig. 4 is a plan view of the rocker shown in detail in Fig. 3.

The numeral 1 indicates the upper leg section or thigh socket, the numeral 2 the lower leg section and the numeral 3 the foot of the artificial leg, which parts may be of the usual or any suitable construction in which the lower leg section is connected to the upper leg section by a suitable knee joint, such for example, as that afforded by the tubular shaft 4.

The numeral 5 indicates the looped cords of suitable shoulder straps or suspenders. In this preferred construction, these shoulder strap cords 5 are passed under and support upper sheaves 6 of floating sheave blocks 7, which, at their lower ends, carry lower sheaves 8.

Located within the lower portion of the upper leg section 1 and pivoted on the tubular knee joint shaft 4, is a rocker in the form of a segmental sheave 9. The numeral 10 indicates a flexible strap, preferably in the form of a cord, the lower end of which is anchored to the back of the intermediate

portion of the lower leg section 2, and the upper end portion of which runs in a peripheral channel of the segmental sheave 9 and is attached to the upper portion thereof, at 11. The numeral 12 indicates a pair of flexible straps, only one of which is shown also preferably in the form of cords, and which are passed through perforations 13 formed in the sides of the upper leg sections 60 1. The inner and lower ends of these straps 12 are anchored to the rocker or segmental sheave 9, preferably by means of screws 14, that are applicable in either of several threaded perforations 15 formed in the 70 wedge of the said rocker 9. The outer ends of these straps 12 are passed over the lower sheaves 8 of the sheave blocks 7, are thence brought downward and secured to the rear lower portion of the upper leg section 1. 75

With the construction above described, the rocker 9 moves on the shaft 4 under very slight friction. In the act of walking, when upward strain is put upon the shoulder strap cords 5 by an upward lift on the shoulder, the rocker 9 will be oscillated upward and the straps 10 and 12, operating through the rocker, will transmit a force to the lower leg section serving to swing the same forward. With this arrangement, it has been 80 found in practice that the lower leg section may be swung forward by shoulder pressure through the connections described, even when the upper leg section is raised to a considerable elevation, or in other words, at a 90 very considerable forward angle to a vertical. Otherwise stated, with this leg it is possible not only to very closely approximate the natural movements in walking, but also to closely approximate a kicking movement. 95

The object in attaching the outer ends of the straps 12 to the upper leg section is to render the upward pressure from the shoulder straps serviceable to hold the upper leg section seated on the stump of the upper leg amputation. Obviously, the device described for producing forward and swinging movements of the lower leg section and for supporting the leg from the shoulder straps, 100 is very simple, of small cost, and has no parts that will easily get out of order.

What I claim is:

1. In an artificial leg, the combination with upper and lower leg sections connected by a knee joint, of a rocker within the artificial leg pivotally mounted at the knee joint,

a connection between said rocker and the lower leg section for swinging the same forward, and a flexible strap connected to said rocker, passed outward through a perforation in the side of the upper leg section and attached to said upper leg section.

2. In an artificial leg, the combination with upper and lower leg sections connected by a knee joint, of a rocker within said leg 15 pivotally mounted at the knee joint, a strap secured at its lower end to the back of the lower leg section, and at its upper end rocked on said rocker and secured thereto, a flexible strap passed through a perforation 20 in the side of the upper leg section and attached at its inner and outer ends, respectively, to said rocker and to said upper leg section, and a shoulder strap connection including a sheave engaged with the looped 25 outer portion of said latter noted strap.

3. In an artificial leg, the combination

with upper and lower leg sections connected by a knee joint, of a rocker within said leg pivotally mounted at the knee joint, a strap secured at its lower end to the back 25 of the lower leg section, and at its upper end rocked on said rocker and secured thereto, a flexible strap passed through a perforation, in the side of the upper leg section and attached at its inner and outer ends, respectively 30 to said rocker and to said upper leg section, and a shoulder strap connection including a sheave engaged with the looped outer portion of said latter noted strap, the connection between the said latter noted 35 strap and said rocker being adjustable.

In testimony whereof I affix my signature in presence of two witnesses.

ANTON M. OPSAL.
